UNITED STATES PATENT OFFICE.

CARL G. HEIBY, JOHN BURKAM, DAVID E. LINDQUIST, FRED L. RIGGIN, EBENEZER W. ALLEN, AND RICHARD LAU, OF SARNIA, ONTARIO, CANADA, ASSIGNEES, BY MESNE ASSIGNMENTS, TO MUELLER METALS COMPANY, OF PORT HURON, MICHIGAN, A CORPORATION OF MICHIGAN.

METHOD OF PRODUCING FORGINGS.

1,373,725.

Specification of Letters Patent.

Patented Apr. 5, 1921.

Application filed January 17, 1918. Serial No. 212,230.

To all whom it may concern:

Be it known that we, CARL G. HEIBY, JOHN BURKAM, DAVID E. LINDQUIST, FRED L. RIGGIN, EBENEZER W. ALLEN, and RICHARD LAU, all citizens of the United States, except ALLEN, a subject of Great Britain, residing at Sarnia, in the county of Lambton and Dominion of Canada, have invented new and useful Improvements in Methods of Producing Forgings, of which the following is a specification.

The present invention relates to methods and apparatus for producing forgings from a slug or blank which has been cast as a unit or cut from suitable stock either cast or rolled, which slug or blank has substantially the quantity of metal necessary to the formation of the article, so that the waste in metal during the finishing operation will be very slight, the forging being substantially in its final form when it leaves the die press.

In the production of articles such as shown in the drawings, herewith, it is highly essential that time, labor, and metal be saved, and it is with the object of reducing the cost that the present invention has been evolved, the result of its practice being that articles free from faults which ordinarily arise in connection with casting, such as sand pits, pipings, and so forth, are eliminated.

In order that the invention may be clear to those skilled in the art, it is illustrated in connection with several different devices in the accompanying drawings.

In said drawings:

Figure 1 is a view of so much of a die press and dies as will illustrate the mechanism for forming the articles.

Fig. 2 is a view of a slug or blank from which articles are formed.

Fig. 3 is a view of a top fuse ring blank after it has been subjected to the action of the press and before trimming.

Fig. 4 shows the top ring blank after trimming.

Fig. 5 shows the fuse ring completed.

Fig. 6 is a view of a bottom ring blank before trimming.

Fig. 7 is a view of the bottom ring blank after trimming.

Fig. 8 is a view of a shrapnel socket blank after forging and before trimming.

Fig. 9 is a view of a shrapnel socket after trimming.

Fig. 10 is a view of the shrapnel socket after machining and finishing.

Figs. 11 and 12 are views showing a union coupling after forging and before trimming, and a union coupling seat after trimming and finishing.

Referring to the drawings by numbers, like numbers indicating like parts in the several views 10 indicates a suitable slug or blank which may be formed individually or cut from suitable stock as may be desired, and while it is shown as cylindrical, it may be of any desired form and dimensions. The slug or blank 10 will have formed therein, first, a centering depression 11 by means of which it may be centered in the die, as will presently appear.

Referring to Fig. 1, it will be seen that there is a bottom die 12 and an upper die 13, the bottom die having preferably a projection 14 designed to engage and center accurately beneath the upper die the slug 10, by engaging the depression 11 with this projection 14 on the bottom die.

The upper die 13 will, of course, be shaped to give the proper contour to the forging, and in forming the top fuse ring illustrated in Figs. 1 to 5, inclusive, the upper die 13 is provided with the circular cavity 15 to form the walls of the fuse ring, and the central punch 16 to form the central opening in the blank, there being also the peripheral cavity 17 to receive the surplus metal and produce a bur or flash, it being desirable that the web and the flash be provided for in order to take care of the slight excess of metal which must be provided for in order that the finished blank shall be of proper formation and density.

The blank 10, when subjected to the action of the die press, produces the half-forged blank shown in Fig. 3, having the centrally disposed web and the peripheral flash. The web 18 not only provides for the disposing of the slight surplus of metal, but it also forms a convenient means for ejecting the blank from the upper die when the die parts

are separated, this ejecting of the blank being effected by the knock-out rod 19, which, as shown in Fig. 1, is centrally placed and capable of being driven downwardly a sufficient distance to eject the blank, the lower end of the punch 19 being in position to engage the web 18.

- After it comes from the press, the blank, shown in Fig. 1, will be subjected to the 10 trimming operation which trimming operation consists in cutting away the web 18 and the peripheral flash 20, bringing the blank to the form shown in Fig. 4. In this form the blank is in shape for the final finishing, 15 which consists in machining and boring, as the necessities of the case may require, suitable cavities and passages, so that the finished top fuse ring will be produced as indicated in Fig. 5.
- 20 The same method is practised in connection with the bottom ring blank shown in its forged form in Fig. 6, and in its trimmed form in Fig. 7, this having the characteristic central web and peripheral flash of the 25 top ring blank, which are trimmed away, and the ring in the form shown in Fig. 7, subjected to the finishing operations.

In Figs. 8, 9, and 10 a shrapnel socket is shown which is formed in the same manner, 30 generally speaking, it being obvious that the die press will be provided with suitably formed dies for securing the different forms produced under the same general method.

Figs. 11 and 12 show the application of 35 the invention to the formation of union coupling seats, Fig. 11 illustrating the untrimmed seat and Fig. 12 showing the finished seat.

In practising the present invention, it will 40 be understood, of course, that the stock or slug, before being subjected to the action of the dies and punches, will be heated to a proper temperature so as to give a blank which may be quickly and readily worked, 45 and in which the metal will flow easily under the action of the dies and punches.

By practising the invention as herein disclosed, articles of various forms may be 50 quickly and readily produced at small expense, and with great saving of time, labor, and metal.

We claim:

1. The method of producing forged blanks 55 having hollow interiors which consists in forming centering means on a suitable slug, positioning said slug by the centering means

on a complementarily formed die, subjecting such centered slug to the combined action of dies and a punch without forcing the punch through the slug, and thereafter 60 trimming away the unpunched webs.

2. The method of producing forged blanks having hollow interiors which consists in forming a centering cavity on a suitable slug, positioning said slug by the centering 65 means on a complementarily formed die, subjecting such centered slug to the combined action of dies and a punch without forcing the punch through the slug, and thereafter trimming away the unpunched 70 webs.

3. Apparatus for forming forged blanks having hollow interiors, comprising a plurality of dies, one, at least, of which has die cavities to give exterior form to the article, 75 and a punch operating to form the hollow interior, said punch and dies being so disposed as to only partially punch the metal, leaving the excess metal in the form of thin webs.

4. Apparatus for forming forged blanks having hollow interiors, comprising a plurality of dies having die cavities for giving exterior form to the article, a punch to form the hollow interior, said punch and dies being so disposed as to only partially punch the metal leaving the excess metal in the form of thin webs, and a knock-out rod adapted to engage a web and eject the forged 80 blank from the die.

5. Apparatus for forming forged blanks having hollow interiors, comprising a die having centering means thereon to engage and center a slug, a coöperating die having a die cavity to give exterior form to the article, a punch to form the hollow interior, said punch and dies being so disposed as to only partially punch the material, leaving excess metal in the form of thin webs, and a knock-out rod mounted in the die head and 95 traversing said punch, said knock-out rod being adapted to engage a web to eject the blank from the die.

In testimony whereof we have hereunto set our hands.

CARL G. HEIBY.
JOHN BURKAM.
DAVID E. LINDQUIST.
FRED L. RIGGIN.
EBENEZER W. ALLEN
RICHARD LAU.
